UNITED STATES PATENT OFFICE.

HARRY C. FOSTER, OF CONNERSVILLE, INDIANA, ASSIGNOR TO INDIANA LAMP CORPORATION, OF CONNERSVILLE, INDIANA, A CORPORATION.

CONNECTER FOR ELECTRIC CIRCUITS.

Application filed July 25, 1927. Serial No. 208,070.

This invention relates to a multiple circuit socket adapted to insure positive contact for three or more mating pairs of current conducting terminals.

5 The chief object of the invention is to provide a socket with suitable means, whereby three or more current carrying conductors will be assured of positive contact when associated with a detachable complementary 10 plug.

The chief feature of the invention consists in the addition of a compensating plate 15 rockingly associated with a terminal plate and normally maintained in contact and arranged so as to be movable as a unit for 20 contact engagement and arranged to have relative movement for insuring positive contact of each of the contacts supported thereby.

25 The full nature of the invention will be understood from the accompanying drawings and the following description and claims:

In the drawings Fig. 1 is a side elevation 30 of the socket associated with the plug. Fig. 2 is a longitudinal sectional view thru the same. Fig. 3 is a transverse sectional view taken on line 3—3 of Fig. 2 and in the direction of the arrows. Fig. 4 is a similar 35 view taken on line 4—4 of Fig. 2 and in the direction of the arrows.

In the drawings 10 indicates a retainer portion of a plug construction having the 40 socket receivable extension 11 and the body portion 12 which supports in insulated relation current carrying wires 13 that terminate in the contact connections 14 associated with each of which is a contact in the form of a screw bolt 15. Herein the plug is shown 45 provided with three current carrying conductors 13. These preferably are arranged in spaced relation, with reference to each other and concentrically arranged with reference to the longitudinal axis of the plug.

50 The multiple socket including the invention includes a tubular shell 16 having a closed end 17 with drawn openings 18, each of which supports a current conducting member 19. As shown in Fig. 4, the openings 18 are arranged in spaced relation relative to each other and are concentrically arranged with reference to the longitudinal axis of the socket and herein three are shown. A terminal plate 20 is similarly apertured 55 at 21 to receive the body portions 22 of the

contact terminal members 23 which are adapted to contact the heads of the screws 15. Concentric with each of the current conducting members 19, which are connected to the respective contact terminal members 22, 60 are the coil springs 24 and these serve to maintain the contacts thru the terminal plate in contact relation with the heads of the screws 15.

To prevent relative rotation in the socket 65 of the said current conducting members 19 and the contact terminals associated therewith, a retaining plate 25 is provided which includes one or more extensions and herein a pair of diametrically arranged extensions 70 26 are shown which extend outwardly and project into longitudinally extending slots 27 and thus plate 25 will permit longitudinal movement but prevent rotation movement of the terminal members. The springs 75 24 bear on said plate.

When three or more current conducting wires or members are employed it is necessary that some sort of compensating arrangement be provided to insure positive 80 contact for or by each of the current conducting contact member terminals. The present form of the invention is herein shown as a portion of a spherical surface 28 formed in the plate 25 and formed coaxially 85 therein, said spherical surface having tangential engagement with the terminal plate 20 and substantially coaxial thereof. Thus the two plates have a coaxial rocking connection and by the aforesaid arrangement 90 positive contact is obtainable and assured for the three or more current conducting members.

The plug and socket herein shown may have any conventional type of detachable 95 connection, or any preferred type of detachable connection, the same forming no part of the present invention.

The invention claimed is:

1. A multiple circuit socket for three or 100 more current conducting lines including a plug receiving and detachably supporting tubular shell, a terminal plate yieldingly mounted therein, at least three current conducting members extending thru the plate 105 for plug contact terminal engagement, yielding means positioned between the end of the shell and said terminal plate, and a compensating plate having a rocking connection with the terminal plate and against which 110

the yielding means bears, whereby the current conducting members are assured of positive plug contact.

2. A device as defined by claim 1, characterized by all of the current conducting members being arranged in spaced relation about the shell axis and the rocking connection being coaxial with the shell axis.

3. A device as defined by claim 1, characterized by the rocking connection between the plates including a portion of a spherical surface engageable by a tangential plane surface.

4. A device as defined by claim 1, characterized by all of the current conducting members being arranged in spaced relation about the shell axis and the rocking connection between the plates being coaxial with the shell axis and including a portion of a spherical surface engageable by a tangential plane surface.

5. In a multiple circuit socket, the combination of a terminal plate having at least

three apertures therein, a current conducting member insulatably supported thereby in each aperture, a compensating plate positioned adjacent said terminal plate and thru which the current conducting members pass, said plates having a coaxial rocking connection therebetween.

6. A device as defined by claim 5, characterized by the addition of an enclosing shell, and yielding means interposed between said shell and said plates for normally maintaining the same in engagement with each other and the current conducting members in plug contact engagement, said plates being movable as a unit longitudinally of said shell, and a slot and tongue connection between one of said plates and said shell for preventing relative rotative movement therebetween.

In witness whereof, I have hereunto affixed my signature.

HARRY C. FOSTER.
